UNITED STATES PATENT OFFICE

162,501

COIN-CONTROLLED LOCK

Donald G. White, Vancouver, British Columbia, Canada

Application November 29, 1949, Serial No. 6,318

Term of patent 14 years

(Cl. D50—7)

To all whom it may concern:

Be it known that I, Donald G. White, a Canadian citizen, residing at Vancouver, British Columbia, Canada, have invented a new, original, and ornamental Design for Coin-Controlled Lock, of which the following is a specification, reference being had to the accompanying drawing, forming part thereof.

Figure 1 is a perspective view of a coin-controlled lock, showing my new design,

Figure 2 is a side elevation thereof, and

Figure 3 is a plan view of the device.

I claim:

The ornamental design for a coin-controlled lock, substantially as shown.

DONALD G. WHITE.
